UNITED STATES PATENT OFFICE

2,009,386

RAZOR BLADE SHARPENING MACHINE

Charles A. Clauss, Bridgeport, Conn., assignor to
General Electric Company, a corporation of New
York

Application March 23, 1934, Serial No. 717,066

7 Claims. (Cl. 51—80)

My invention relates to razor blade sharpening machines and more particularly to a razor blade sharpening machine driven by an electric motor.

An object of my invention is to provide an improved motor-driven razor blade sharpening machine which requires a minimum number of parts and which may be easily and cheaply manufactured.

Another object of my invention is to provide a razor blade sharpening machine in which the sharpening rolls are arranged in a detachable roll unit that may be easily removed from the machine in case of defective or worn out parts.

Another object of my invention is to provide a motor-driven razor blade sharpening machine having a resilient vibration absorbing base which may be easily detached in order to facilitate removal or repair of the electric motor and switch contained therein.

A still further object of my invention is to provide an improved form of sharpening roll for use in razor blade sharpening machines of the type described.

What I consider to be novel and my invention will be better understood by reference to the following specification and appended claims when considered in connection with the accompanying drawing in which Fig. 1 is a perspective view of a sharpener; Fig. 2 is a side elevation in cross section; Fig. 3 is an end elevation in cross section; Fig. 4 is a partial end elevation in cross section showing the roll supports in the open position.

In the drawing, 10 indicates a plate on which the sharpening roll unit is mounted. The sharpening roll unit includes a sheet metal frame 11 in which sharpening rolls 13 and 14 are journaled by means of pins 15 and 16. Roll supports 17 and 18, preferably made in the form of protective covers for the sharpening rolls, are pivotally supported on pins 15 and 16. Sharpening rolls 19 and 20 are loosely journaled in roll supports 17 and 18 by pins 21 and 22. Relative radial movement of these rolls 19 and 20 is permitted by the oval openings or guides in which pins 21 and 22 are journaled as best shown in Fig. 1.

Roll support 18 is biased to the open position by spring 23 which is secured to projections 24 and 25 on frame 11 and roll support 18 respectively. Roll supports 17 and 18 are connected by a linkage preferably formed as shown by a projection 26 on the lower extension of support 18 which rides in a curved slot 27 formed in the lower extension of support 17. The biasing effect of spring 23 is transmitted to support 17 through the linkage described, also the pivotal movement

of the roll supports 17 and 18 is synchronized thereby. A flat spring member 28 is secured to plate 10 by means of screw 29 as best shown in Fig. 3. Flat spring member 28 is provided with a slot 30 and an upwardly projecting thumb piece 31. Roll support 17 is provided with a lower projection 32. When the roll support 17 is in the vertical or operative position projection 32 falls in slot 30, thus retaining support 17 in the vertical position. At the same time support 18 is also retained in the vertical position through linkage 26—27 against the bias of spring 23. The roll supports are thus retained rigidly in the vertical or operative position and vibration is minimized. Since spring 23 is secured to the frame 15 rather than between the roll supports it is subjected to a single stretch which further reduces vibration. When thumb piece 31 is depressed by the operator the flat spring 28 is moved downward, releasing projection 32 from slot 30 and the roll supports 17 and 18 are moved to the open or inoperative position, shown in Fig. 4, under the influence of biasing spring 23. Tapered pins 33 and 34 are provided for positioning the razor blade between the rolls. These pins 33 and 34 are staked to frame 11 by screws 35 and 36. The entire sharpening roll unit is secured to plate 10 by a single screw 37 as best shown in Fig. 2. Upon disengagement of screw 37 the entire sharpening unit may be removed, thus greatly facilitating the replacement of defective or worn out parts. Since the blade supporting pins 33 and 34 are a part of the sharpening roll unit adjustments are obviated which would be required if new rolls were simply put in.

The construction of the rolls is indicated in Fig. 2 in which roll 19 is shown with its stropping or sharpening surface 38 embedded in a spiral groove in the wooden body member. The other sharpening rolls, 13, 14 and 20 are provided with similar stropping surfaces so positioned that the adjacent convolutions of one roll are spaced between the adjacent convolutions on the other roll to compensate for wear of the stropping surfaces. The ends of the wooden body members 35 are tapered and metal ferrules 39 are forced on over the tapered ends also engaging and holding the ends of the sharpening material 38. Metal pins 15, 16, 21, 22 are driven into the ends of the wooden body of the roll. A sharpening roll is thus provided which is economical to manufacture and is assembled in such manner that the sharpening material is securely fastened to the body of the roll.

Grooved collars 40 are carried by the pins 15, 55

16, 21 and 22 and arranged to turn freely thereon. Spring members 41 and 42 are provided with hooked ends which engage the grooves in collars 40. The collars are restrained from 5 turning by the hooked ends of springs 41, 42 and wear of the latter is avoided which would be present if the springs were in direct contact with the rotating pins. Springs 41 and 42 in addition to compensating for the wearing of the sharpening 10 or stropping surface provide a spring bias between the rolls which remains constant and provides any sharpening pressure desired to accomplish the sharpening of the razor blade. As pointed out above, the oval openings in supports 15 17 and 18 in which rolls 19 and 20 are journaled permit relative radial movement of the sharpening rolls.

Motor 43 is supported on the underside of plate 10 having self-aligning bearings 44 and 45 as 20 is described in a copending application Serial No. 690,049, filed by Noble H. Wats and the present inventor, Charles A. Clauss, and assigned to the same assignee as the present invention. The energization of motor 43 is controlled by contacts 25 46 and 47 which are carried by flat spring members 48 and 49 respectively. Spring member 49 is moved to the operative position by projection 50 on the lower part of roll support 18. On the end of shaft 51 of motor 43 a worm gear 52 is 30 secured which engages gear 43 secured to roll 13 and a corresponding gear secured to roll 14. Gear 54 secured to roll 19 meshes with gear 53 on roll 13, a similar pair of meshing gears being provided on rolls 14 and 20.

35 The motor and switching means are enclosed by a resilient base 55 preferably made of rubber. The base member 55 is hollow and cup-shaped, being provided with an interior groove 56 adjacent its upper edge. A tongue 57 on the periphery of plate 10 engages the groove 56. Resilient base 55 is provided with vacuum cups 58 which hold the device steady while in operation. The use of a resilient base as shown is very advantageous not only because of its vibration absorbing qualities but also in that it may be quickly applied or removed thus facilitating assembly, inspection and repair of the motor and switch.

In operation, the razor blade to be sharpened 50 is placed on tapered pins 33 and 34. Roll supports 17 and 18 are then grasped by the operator and moved to the vertical position as shown in Fig. 3. Projection 32 drops into slot 30 of spring member 28 thus retaining the roll supports and 55 sharpening rolls in the operative position against the bias of spring 23. At the same time projection 50 on roll support 18 moves downward causing spring member 49 to be depressed and thus closing contacts 46 and 47 so that motor 43 is energized when the rolls are in the operative 60 position. When the sharpening operation has been completed the operator pushes thumb piece 31 downward, releasing projection 32 from its engagement with slot 30. Upon the release of 65 projection 32 the roll supports 17 and 18 move to the open position, shown in Fig. 4, under the bias of spring 23 and through the intermediation of linkage 26—27. At the same time projection 50 on roll support 18 moves upward to allow contacts 46 and 47 to open so that motor 43 is de- 70 energized.

From the foregoing it will be seen that a motor-driven razor blade sharpening machine is provided which may be easily assembled and 75 disassembled both during the process of manu-

facture and for purposes of repair. The razor blade sharpening machine described requires a small number of parts and is easy and safe to operate as well as being economical to manufacture.

5

What I claim as new and desire to secure by Letters Patent of the United States is:

1. A razor blade sharpening machine comprising a plate, a motor and a detachable sharpening roll unit supported on opposite sides of said plate, 10 said sharpening unit including a frame, a pair of sharpening rolls journaled in said frame, a pair of opposed roll supports pivoted on the ends of said rolls, each of said supports carrying an additional sharpening roll journaled therein, 15 means interconnecting said motor and all of said rolls, a spring secured to said frame and to one of said supports to bias the said support to the inoperative position, linkage means arranged to transmit the biasing force of said 20 spring from said one support to the second support, and a switch, controlling the circuit of said motor, movable to the closed position by a projection on one of said supports when said support is moved to the operative position.

25

2. A razor blade sharpening machine comprising a plate, a motor and a detachable sharpening roll unit supported on opposite sides of said plate, 30 said sharpening unit including a frame, a pair of sharpening rolls journaled in said frame, a pair of opposed roll supports pivoted on the ends of said rolls, each of said supports carrying an additional sharpening roll journaled therein, means interconnecting said motor and all of said rolls, a spring secured to said frame and to one of said supports to bias the said support to the inoperative position, linkage means arranged to transmit the biasing force of said spring from said one support to the second support, a manually 35 releasable catch member in the path of a projection on one of said supports and engageable therewith when said supports are in the operative position, and a switch, controlling the circuit of said motor, movable to the closed position by a projection on one of said supports when 40 said support is moved to the operative position.

45

3. In a machine of the type described, a sharpening roll unit comprising a frame, a pair of sharpening rolls journaled in said frame, a pair of opposed roll supports pivoted on the ends of 50 said rolls each of said supports carrying an additional sharpening roll journaled therein, means to position a razor blade between said rolls, and linkage means to cause simultaneous movement of said supports including a projection on one 55 of said supports positioned to slide in a curved slot provided in the other of said supports.

55

4. In a machine of the type described, a sharpening roll unit comprising a frame, a pair of sharpening rolls journaled in said frame, a pair 60 of opposed roll supports pivoted on the ends of said rolls, each of said supports carrying an additional sharpening roll journaled therein, means to position a razor blade between said rolls, a spring bias between one of said supports below 65 its pivot point and said frame and linkage means interconnecting said supports whereby the biasing force of said spring is transmitted to the second support.

65

5. In a machine of the type described, a sharpening roll unit comprising a frame, a pair of sharpening rolls journaled in said frame, a pair of opposed roll supports pivoted on the ends of 70 said rolls, each of said supports carrying an additional sharpening roll journaled therein, means 75

to position a razor blade between said rolls, linkage means interconnecting said supports whereby their pivoted movement is synchronized, a projection on one of said supports and a spring biased catch member engageable with said projection to prevent rotation of said supports.

6. In a machine of the type described, a sharpening roll unit comprising a frame, a pair of sharpening rolls journaled in said frame, a pair of opposed roll supports pivoted on the ends of said rolls, each of said supports carrying an additional sharpening roll journaled therein, means to position a razor blade between said rolls, linkage means interconnecting said supports, a spring bias between one of said supports and said frame and a catch member engageable

with one of said supports to prevent rotation of the supports under the influence of said spring and linkage.

7. In a machine of the type described, a sharpening roll unit comprising a frame, a pair of sharpening rolls journaled in said frame, a pair of opposed roll supports pivoted on the ends of said rolls, each of said supports carrying an additional sharpening roll loosely journaled therein, means to position a razor blade between said rolls, a freely turning grooved collar carried at each end of said rolls and biasing means engaging said collars to urge adjacent rolls into engagement.
